DIFFERENTIAL PRESSURE TRANSMITTER

Roger B. Kerr, Topsfield, Clement F. Taylor, Danvers,
and Frank Baranowski, Jr., Lynnfield Center, Mass., as
signors to General Electric Company, a corporation of
New York

Filed Dec. 15, 1965, Ser. No. 184

Term of patent 14 years

(Cl. D55—1)

FIG. 1

FIG. 4

FIG. 2

FIG. 3

FIGURE 1 is a perspective view of a differential pressure transmitter embodying our new design; and

FIGURES 2, 3 and 4 are, respectively, top, side, and end views of the differential pressure transmitter shown in FIGURE 1.

We claim:

The ornamental design for a differential pressure transmitter, as shown and described.
